UNITED STATES PATENT OFFICE.

EMIL KLAHN, OF WEST HOBOKEN, NEW JERSEY.

DESIGN FOR A PEDAL.

SPECIFICATION forming part of Design No. 30,351, dated March 14, 1899.

Application filed February 11, 1899. Serial No. 705,349. Term of patent 7 years.

To all whom it may concern:

Be it known that I, EMIL KLAHN, a citizen of the United States, and a resident of West Hoboken, in the county of Hudson and State 5 of New Jersey, have invented and produced a certain new and original Design for Pedals for Foot-Driven Machines, of which the following is a specification.

My invention is a new design for pedals for 10 foot-driven machines, which is illustrated in the accompanying drawings, forming part of this specification, and in which—

Figure 1 is a top view, Fig. 2 is a side view, and Fig. 3 is an end view, of a pedal embodying my design.

As shown in the drawings, the leading or material feature of the design consists of a cylinder A, from the opposite sides of which spring outwardly and upwardly curved wings 15 a. The diagonally opposite ends of the opposite wings a are extended upwardly into horn-shaped projections at a', and the ends of cylinder A appear slightly enlarged in diameter, so as to give the appearance of rings 20 on the ends of the cylinder, as at B B.

The several portions of the pedal may be engraved, chased, or otherwise ornamented, and may be of any brilliant metallic finish or japanned.

As shown, the wings are perforated and 30 their upper edges serrated to give them a useful, light, and more ornamental appearance.

The essential feature of the design is the cylinder with diametrically opposite upwardly and outwardly curved wings or members, substantially as shown.

Having thus described my original design, what I claim as new, and desire to secure by Letters Patent, is—

The design for a pedal, substantially as 40 herein shown and described.

Signed at New York, in the county of New York and State of New York, this 6th day of February, A. D. 1899.

EMIL KLAHN.
